UNITED STATES PATENT OFFICE.

GEORGE A. SIMS, OF ERIE, PENNSYLVANIA.

WATER-HEATER.

1,143,866.

Specification of Letters Patent. Patented Aug. 3, 1915.

Application filed December 19, 1914. Serial No. 878,179.

To all whom it may concern:

Be it known that I, GEORGE A. SIMS, a citizen of the United States, residing at Erie, in the county of Erie and State of Pennsylvania, have invented certain new and useful Improvements in Water-Heaters; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in water-heaters, and particularly to a type of water-heater adapted to utilize the exhaust gases from internal combustion engines.

The object of my invention is the construction of the heater of substantially duplicate sections preferably cylindrical in form, the lowermost section being provided with a water inlet and the uppermost section with a water outlet, the sections of the heater being provided with peripheral flanges which engage each other and form the outside shell of the heater when superimposed upon each other, and centrally secured together by means of screw threaded sleeves whereby the expansion and contraction of the sections are uniform.

The features of this invention are herein-after fully set forth and explained and illustrated in the accompanying drawings, in which:

Figure 1, is a view of my improved water-heater partly in elevation and partly in section. Fig. 2 is an enlarged view in section of one of the duplicate sections of the heater. Fig. 3, is a transverse section of the heater on the line $x-x$ in Fig. 1, looking in the direction of the arrow.

In the construction of my improved water-heater thus illustrated, A, represents the base of the heater preferably supported on legs a. This base A, has formed therein a chamber A', and is provided with a pipe B, for conveying the exhaust gases of the engine into the chamber A'.

Upon the base A, is superimposed the lowermost section C, of the heater, the flange C', thereon resting in the circumferential groove a', in the base A, where it is preferably cemented therein; the section C, is further preferably secured to the base A, by means of bolts c. This section C, is pro-

vided at one side with a water inlet C², and is provided with a screw plug C³, which closes the central opening C⁴, in the bottom of the section C, to prevent the passage of water into the chamber A'. In this section then are also vertical passages C⁵, by means whereof the gases pass up through the section C, into an annular chamber d, between the section C, and the next superimposed section D.

The intermediate sections D, between the lowermost section C, and the topmost section, are clearly illustrated in Fig. 2, and are each provided with a circumferential flange D', around its base, and a circumferential flange D², around its top; the base flange D', fitting into the top flange D², as clearly shown in Fig. 1, which flanges are preferably cemented to each other, the spaces between the sections forming the chambers d. Leading vertically through each of these sections are tubes D³, for conveying the hot gases from one of the chambers d, to the next chamber d, above it.

To convey the water from one section to another, I provide central internally screw threaded openings E, in the bottom and top of each section, and connect these openings E, by means of externally screw threaded sleeves E'. The water passes up through the lower sleeve E', into the section D, under the central web D⁴, therein and then under said web to the annular passage D⁵, and back over the web D⁴, to the central sleeve E' in the top of the section and then through said sleeve into a like sleeve E', above it, as clearly shown by the arrows in Fig. 2, and so on up until it reaches and enters the topmost section F, from which it is discharged through the outlet pipe G, the top central opening F', in the top of the topmost section F, being closed by a screw plug F².

Upon the top of the topmost section F, there is a top plate H, provided with a downwardly extending circumferential flange h, which engages the circumferential flange f, on the top of the section F, where it is secured by means of cement. The top plate H, is preferably further secured to the section F, by means of bolts h'. To the central part of the plate H, there is secured a gas discharge pipe I, through which the gases passing up through the heater are discharged.

In operation the hot gases enter the heater

through the pipe B, passing into the chamber A' and thence upward through the tubes C⁵, into the chamber d, and thence through the tubes D⁸, successively from one 5 chamber to another between the successive sections until it reaches the chamber at the top of the section F, from which they pass out through the gas discharge pipe I. Meanwhile the water to be heated enters the 10 lowermost section C, through the pipe C², and from it into and through the intermediate sections D, as indicated by arrows in Fig. 2, until it reaches the top section F, from which it is discharged through the 15 pipe G. The important features of this invention are cheapness and novelty of construction, freedom from accident when in operation, and efficiency from the large heating surface to which the water is exposed 20 during its passage through the heater.

Having thus described my invention so as to enable others to construct and utilize the same, what I claim as new and desire to secure by Letters Patent is:—

25 1. In a water-heater the combination of a series of integral sections having heating fluid passages therethrough and therebetween and water passages therein, superimposed upon each other, with the water passages 30 therein centrally connected, and flanges on said sections inclosing the spaces between the same, substantially as set forth.

35 2. In a water-heater, the combination of a series of integral sections superimposed upon each other, each having heating fluid 40 passages therethrough and therebetween, and water passages therein, central water connections between said sections, over-lapping flanges on said sections inclosing the 45 spaces therebetween, a water inlet in the lowermost section, a water outlet in the topmost section, a gas inlet communicating with the gas passages in said sections, and a gas outlet for discharging the hot gases from the 50 topmost section, substantially as set forth.

3. An integral water-heater section having heating fluid passages therethrough, water passages and central water inlet and outlet openings, overhanging integral flanges 50 on said sections one of which is of less diam-

eter than the other, substantially as set forth.

4. An integral water-heater section having heating fluid passages therethrough, water passages and central water inlet and 55 outlet openings therein, a horizontal web dividing said water passages so that the water flows from the inlet outward under said web, overhanging integral flanges on said sections, one of which is of less diameter 60 than the other, and inward to the outlet above said web, substantially as set forth.

5. The combination in a water-heater of a series of integral sections fitting upon each other, each having lower and upper water 65 passages communicating at the peripheries of the sections, a central water inlet and an outlet at the center of the top and bottom of each section, and vertical heating fluid 70 passages through each section, flanges on each of said sections adapted to telescopically fit one within the other, and water connections between the outlet of one section and the inlet of another section, substantially as set forth. 75

6. The combination in a water-heater of a series of integral circular sections the peripheral walls of which project beyond the flat sides of the body portion thereof and are adapted to telescopically fit each other 80 and form the outer wall of the heater, having lower and upper water passages connecting at the peripheries of the sections, a central water inlet and an outlet at the top and bottom of each section, and vertically heating 85 fluid passages through each section, water connections between the outlet of one section and the inlet of the next section, a water inlet in the lower section and a water outlet in the top section, a base secured to 90 the bottom section having a heating fluid inlet therein, and a plate secured to the top section having a heating fluid outlet therein, substantially as set forth. 95

In testimony whereof I affix my signature, in presence of two witnesses.

GEORGE A. SIMS.
